UNITED STATES PATENT OFFICE.

HENRY G. GRIFFIN, OF GRAND RAPIDS, MICHIGAN.

FLUSHING-VALVE.

1,169,326.

Specification of Letters Patent. Patented Jan. 25, 1916.

Application filed March 27, 1914. Serial No. 827,525.

To all whom it may concern:

Be it known that I, HENRY G. GRIFFIN, a citizen of the United States, residing at Grand Rapids, in the county of Kent and 5 State of Michigan, have invented certain new and useful Improvements in Flushing-Valves, of which the following is a specification.

My invention relates to improvements in 10 flushing valves for use on hopper closets, especially when exposed to intense cold, and its objects are: first, to provide a flushing valve that will prevent the contact of water with the actuating spring, and the danger 15 of freezing the spring in very cold weather and thus rendering the valve inoperative, and, second, to provide a means whereby the forming of valve seats may be dispensed with. I attain these objects by the mechanism illustrated in the accompanying drawing, in which—

Figure 1 is an elevation of a closet bowl and the upper end of the flushing valve barrel in section showing the manner of connecting the closet seat with the flushing appliances. Fig. 2 is a vertical section of the flushing valve proper showing its several passageways and the application of the valve. Fig. 3 is an elevation of the main 20 trap, and Fig. 4 is a vertical section of an ordinary flushing valve and its connections, entered for the purpose of illustrating the difference in construction and operation of the two valves.

Similar numerals and letters refer to similar parts throughout the several views.

I will first proceed to describe the action of the valve in common use, for the purpose of later making the advantages of my valve 40 the more apparent. With ordinary valves the general construction is somewhat similar to that shown in Fig. 4 where the water is shut off from the city main by means of a seated valve, as 10', and when it is desired 45 to flush a closet said valve is raised from its seat and water may flow into the barrel 7'. At this time the packing 10' is raised upward sufficiently to close the passageway to the outflow pipe 6' and the water may 50 flow through the port b into the pipe 8'' and thence out through the port a into the upper end of the barrel whence it flows by the collar 15' and the spring 9' through the pipe 5' and to the closet basin. In this operation 55 the valve 10' is actuated through the stem 8' by means of an actuating lever from the

closet seat acting upon the bar 4', exactly as with my valve connections, as hereinafter fully described.

It will be readily understood that if water 60 is forced to flow around the spring 9' and out of the port 5' to reach the closet basin, in very cold weather and these parts unprotected, the water will be held from a clean free flow out of the barrel 7' by the spring 65 9', and will, in a short time, become frozen around the spring and the valve stem to such an extent as to render the valve wholly inoperative. To obviate this difficulty, and prevent any water from coming in contact 70 with the actuating spring 9, in my valve, I form a body A having a main barrel A A and branch outlets B and 6. The valve 10 is held, normally, in the position indicated by its solid lines in Fig. 2, when the flow of 75 water from the main pipe 11 is wholly shut off and no water flows into the barrel A. In this position any water that may flow back from the pipe 5, flows directly out of the pipe or port 6 to the sewer, and there is al- 80 ways enough water between the outflow pipe and the outflow opening B to form a perfect trap.

If the valve 10 is raised to the position indicated by its dotted lines in Fig. 2 the 85 passageway between the opening B and the opening 6 is closed and that between the water main 11 and the opening B is free for the flow of water from the main pipe through the passageway B and the pipe 5 90 for the free flushing of the basin 1, but in no case can any water rise above the outflow pipe 6 so as to come in contact with the spring 9, so that this spring is always free to actuate the valve, no matter what 95 the weather may be or how much the spring may be exposed to the cold. This class of closets are supposed to be used, only, where it is necessary to place them out of doors or in places where they are exposed to extreme 100 cold, and the flushing valve A is placed low enough in the ground or in a warm basement to avert the danger of ever being affected by the frost, but just above the location of the main closet trap 13 so that any 105 water flowing out of the outflow pipe 6 in my valve, or 6' in the ordinary valve, will flow into the pipe 12 above the trap 13, so there will be no danger of sewer gases passing through the trap 13 into the barrel 7, 110 by the course hereinbefore described. It is, of course, to be understood that any water

or other matter passing into the trap 13 will pass out through the end 16 into the sewer system in the usual manner.

The valve 10 is opened or raised to the position indicated by its dotted lines in Fig. 2 by means of an arm 3 that is secured to the seat 2 of the closet bowl 1 so that when the seat 2 is pressed downward upon the top of the bowl 1 the arm 3 will be forced upward and will raise the bar 4, as indicated by its dotted lines in Fig. 1, and, through the valve rod 8 the valve 10 is raised with it, and the valve 10 is forced downward against the pressure of the water below it, to position below the opening B, by means of the spring 9 acting on the collar 15. It is necessary, of course, for the spring 9 to be capable of exercising considerably more pressure on the collar 15 than the pressure of water below the valve 10 so as to positively insure the closing of this valve when the seat 2 is relieved and allowed to assume its normal position indicated by its solid lines in Fig. 1. This seat 25 is pivoted to the closet bowl or basin, as indicated at 17 so the arm 3 always moves in the reverse direction from the seat.

It will be noted that with this construction it is impossible for any water to come 30 in contact with the spring 9 as no water from the main 11 can pass the valve 10 whether it is in its normal position at 10 or in its raised position as indicated by its dotted lines, and the outflow of water 35 through the pipe 6 is so free that it will

easily carry off all water that sets back from the pipe 5, after the valve 10 has been returned to its normal position, without allowing it to rise above the said outflow pipe, hence the spring 9 and all portions of the body or pipe 7 is dry above the pipe 6 so that no ice can form at any time or in any manner.

What I claim as new, and desire to secure by Letters Patent, is:

In a flushing valve, a long, vertically disposed barrel having a direct connection with a water main, a pipe extending upward from the upper end of the barrel forming a housing for a long valve rod, a long valve rod in said housing, a cylindrical valve secured to the lower end of said rod, a spring connected with said rod to hold said valve normally closed against the passage of water from the water main into the valve barrel, a discharge opening through the side of the valve barrel above the normal position of the valve, a second opening through the side of the barrel above the discharge opening with space between the two side openings to perfectly seat the valve, and means for raising and lowering the valve from any desired distance above the valve barrel.

Signed at Grand Rapids, Michigan, 65
March 20, 1914.

HENRY G. GRIFFIN.

In presence of—

ARTHUR W. SNOWDEN,
I. J. CILLEY.
